UNITED STATES PATENT OFFICE.

OWEN W. TAFT, OF BROOKLYN, NEW YORK.

IMPROVEMENT IN STEELS FOR SHARPENING KNIVES.

Specification forming part of Letters Patent No. 147,705, dated February 17, 1874; application filed December 13, 1873.

To all whom it may concern:

Be it known that I, OWEN W. TAFT, of Brooklyn, in the county of Kings and State of New York, have invented a new and Improved Knife-Sharpening Steel, of which the following is a specification:

My invention relates to a knife-sharpening steel possessing peculiarities of construction calculated to render it much more efficient and for a longer period than other steels. It consists in a series of blades set radially around a rod or stock which is attached to a handle of suitable form, as hereinafter described.

Figure 1 is a side elevation of my improved steel with part in section. Fig. 2 is a cross-section on the line *y y* of Fig. 1. Fig. 3 is a longitudinal section of one of the bolsters.

Similar letters of reference indicate corresponding parts.

A is a rod of iron or steel, about as long as the ordinary steel rod used for sharpening table-knives, and about the same size, on the upper end of which is a permanent head, *B*, considerably larger at the lower end than the rod and having radial undercut notches *a* for the reception of the ends of a number of long steel blades, *C*, arranged edgewise to and parallel with the rod around it at intervals of about equal width to the blades themselves, and secured at the other ends by the collar or bolster *D*, which also has radial undercut notches *a* for the ends of said blades, and is screwed up to hold them fast by the nut *E* and handle *F*, the latter being secured upon the rod by being screwed up against the bolster. These blades are employed for the benefit of the angles of their outer edges for knife-sharpening

purposes, which are more efficient than can be formed on a steel rod by the concave flutes or grooves, or the file surfaces with which steels are armed, as their form is better adapted for action on the knife-edge; and it is such that the edges do not become dulled by wear, but are adapted to be self-sharpening, or if necessary they can be filed or ground sharp.

This arrangement of the blades of the steel is better than a construction of the blades and the rod by planing out the spaces between them in a large solid rod, because of greater economy of construction; also, because the blades being made separately can be hammered and tempered better; and, also, because in case a blade is defective it can be removed and another can be put in its place.

The rod *H* has an extension, *G*, with a notch, *H*, to adapt it to be used as a skewer-pull. Also, the point *K* of the same and a curved blade or cutter, *L*, which is pivoted in a circumferential recess of the head *B*, constitute, in connection with the handle of the steel, an efficient can-opener; but I do not here claim these devices, since I purpose making them the subjects of other Letters Patent.

Having thus described my invention, I claim as new and desire to secure by Letters Patent—

The combination of a set of radial blades, *C*, with a rod or stock, *A*, and a handle, *F*, in the manner described, for sharpening knives.

OWEN W. TAFT.
